UNITED STATES PATENT OFFICE.

TOMOJI YAMAKISHI, OF BELLEVUE, WASHINGTON.

AUTOMATIC RAILROAD SWITCH.

Application filed October 24, 1927. Serial No. 228,262.

This invention relates to improvements in railway switches and automatic control means therefor in the use of which a traveling train may be switched in either direction relative to the main track and may be returned to the main track after completing a loop or other turn without manual operation of the switch other than as may be necessary in the setting by the engineer of a trip on the locomotive.

The main object of the present invention is the provision of a switch involving switch points connected for unit movement and adapted to be moved in one direction through the medium of an engine-carried trip, the switch points being locked in the set direction through mechanism controlled by the wheels moving on the track in advance of the switch.

The invention is illustrated in the accompanying drawings, in which:

Figure 1 is a plan view of a portion of the track showing the improved switching mechanism.

Figure 2 is a side elevation illustrating particularly the lock control mechanism.

Figure 3 is a section on line 3—3 of Figure 1, with the switch point set for travel in one direction.

Figure 4 is a similar view with the switch point set for travel in the opposite direction.

Figure 5 is a diagrammatic plan illustrative of the track arrangement.

Figure 6 is a section on line 6—6 of Figure 4.

The present improvement contemplates the use of switch points 1 and 2 movably supported at 3 on one of the usual track ties 4, these respective switch points forming the terminals in the present illustration of the inner rail 5 of a loop or other siding, the other rails 6 of which loop form continuations of the main rails 7 and 8.

The switch points, which are of the usual rail formation reduced at their ends to form the points, are controlled by a locking mechanism including a locking bar 9 vertically movable in guides 10 on one of the ties 4 adjacent the movable ends of the switch points, the bar 9 being normally influenced in the upward direction by a spring 11. The bar 9 is formed with a transverse opening 12 to receive the operative end 13 of a controlling bar 14 slidably guided on the particular tie 4 through the medium of a pin and slot connection 15, the tie being provided with an additional pin 16 working in the slot to limit

the movement of the controlling bar in one direction.

Mounted lengthwise of one of the main rails, as 8, is a bar 17 having bearing in suitable pedestals 18 mounted on the ties. This bar 17 has a rigidly connected depending arm 19 connected by a link 20 with one end of the controlling bar 14. Fixed on the bar 17 at appropriate intervals, as by set-screws 21, are plates 22, the free edges of which extend closely adjacent the track rail 8.

A spring 23 is arranged to cooperate with the bar 17 so as to turn the bar to normally hold the free edges of the plates 22 on a plane above the rail 8, as clearly shown in Figure 3. The bar 17 is continued lengthwise of the loop rail 6 in the form of a bar 24 having spring-operating means 25 and provided with plates 26 arranged similar to 23 and operating identically with the plates 22.

The switch points 1 and 2 are connected adjacent their free ends by a tie bar 27 having a central projection 28 terminating in a bail end 29 to seat in a corresponding recess 30 in the end of a lever 31 pivoted intermediate its ends at 32 upon a tie 4 and provided at the end opposite the connection with the tie bar with an upstanding projection 33.

A spring 34 connected to one of the ties 4 and bearing against the end of the lever 31 tends to move the lever in a position to hold the switch points in what may be termed a normal position; that is to say, with the points closed with respect to the main rail 8 and loop rail 6 and open with respect to the main rail 7 and loop rail 5.

In this normal position of the parts, the controlling bar 14 is moved to its limit toward the left in Figures 3 and 4, causing the inclined portion of the operative end of said bar to cooperate with the lower wall of the opening 12 of the locking bar 9 and depress said bar. The switch points are then held in their normal position by the spring 34 moving the lever 31 in the particular direction.

Assume a train traveling in the direction of the arrow on the rails 7 and 8 and desiring to continue onto the loop rails in the direction of the curved arrow, Figure 5. An appropriate trip on the engine is lowered to engage the trip 33 to deflect the lever 31 into the dotted line position of Figure 1. Simultaneously with or immediately preceding this engagement, the wheels of the

locomotive and thereafter the wheels of the cars of the train ride upon and depress the free edges of the plates 22, rocking the bar 17 and moving the controlling bar 14 in the direction of the arrow (Figure 3). This withdraws the pointed end 13 of the controlling bar from the opening in the locking bar and permits the latter to move upwardly under the influence of the spring. As the lever 31 is shifted, the switch point 1 moves into contact with the rail 7 and the switch point 2 moves away from contact with the rail 8. As this movement continues, the locking bar 9 rides upwardly immediately adjacent to the base of the switch point 1, holding the switch locked in this position.

As the train fully enters the loop and rides off of the plates 22, the spring 23 operates to restore the parts to normal position, with 20 drawing the locking bar 9 from locking position relative to the switch points and permitting the spring 34 to operate the lever to restore the switch points to normal position. As the train completes the loop and again 25 reaches the main track, the switch points are deflected by the wheels to permit the desired movement and then will immediately return to normal position through the influence of the spring 34.

30 The plates 26 and cooperating parts serve of course to maintain the locked position of the switch until the train has completely left the switch area.

If the train direction is opposite to that described, no movement of the lever 31 is 35 required.

It will of course be apparent that the use of the automatic switch hereinbefore described constructed according to the present invention does not in any way interfere with 40 the installation and operation of the usual hand-operated switch, and in fact provision may be readily made for operating the switch by hand if and in the event the automatic means should fail of actuation. That is to 45 say, the use of this switch may be made additionally protective of switching operations over and in connection with the usual hand-operated switch.

What I claim to be new is:

In a switch system, the combination with 50 a pair of main rails, a pair of switch rails whose terminals are swingable between the main rails, a lever having one of its ends pivoted to the switch, a spring for holding 55 said lever in normal position, a rock shaft, pressure plates on the rock shaft, a resiliently tensioned switch rail locking device, and a tapered slideable controlling bar linked to said rock shaft and frictionally engag- 60 ing said rail locking device to unlock the same whenever a vehicle contacts with the pressure plates on the rock shaft.

In testimony whereof I affix my signature.

TOMOJI YAMAKISHI.
